UNITED STATES PATENT OFFICE.

JOHN V. McNAMARA, OF TROY, NEW YORK.

COLLAR.

Application filed November 2, 1921, Serial No. 512,277. Renewed October 31, 1923.

To all whom it may concern:

Be it known that I, JOHN V. McNAMARA, a citizen of the United States, residing at Troy, in the county of Rensselaer and State 5 of New York, have invented certain new and useful Improvements in Collars, of which the following is a specification, reference being had therein to the accompanying drawings.

10 This invention relates to collars, and the object of the invention is the construction of a strong and durable yet neat collar for use or wear by a person.

Another object of the invention is the 15 method or process of constructing a collar, whereby the corners of the body of the collar are greatly reinforced and strengthened, as well as the ends and one of the longitudinal edges of the body.

20 With these and other objects in view, my invention comprises certain novel combinations, constructions and arrangements of parts as will be hereinafter described, illustrated in the accompanying drawings, and 25 more particularly pointed out in the appended claims.

In the drawings:

Figure 1 is a fragmentary view of the 30 blank of the body of the collar as first cut.

Figure 2 shows the blank with the first line of fold at the corner.

Figure 3 shows the blank with the first corner fold.

35 Figure 4 is a view showing end of blank after first fold and ready for second fold.

Figure 5 is a fragmentary view of the blank showing the second line of fold.

Figure 6 shows the second fold of the 40 blank.

Figure 7 is a fragmentary view of the blank showing end of blank after second fold and ready for third fold.

Figure 8 is a fragmentary view of the 45 blank showing line for first longitudinal creasing on a creasing machine.

Figure 9 shows first folding along line of creasing, per Fig. 8.

Figure 10 shows second line of creasing 50 and end folding.

Figure 11 shows the blank with the end and longitudinal folds completed, and in dotted lines are shown the different folds

that have taken place in the process of construction of the blank.

Figure 12 shows a double row of stitching on one end.

Figure 13 shows a double row of stitching on two ends and one longitudinal edge.

Figure 14 shows partly an unstitched 60 body and partly a body with a double row of stitching along one end and one longitudinal edge.

Figure 15 is a fragmentary, sectional view 65 of the body of a collar.

Figure 16 is a fragmentary, perspective sectional view of the body of the collar showing the effect of creasing machine on line of fold.

Figure 17 is a perspective view of a 70 finished collar constructed in accordance with the present invention.

Referring to the drawings by numerals, 1 designates a blank, the outer longitudinal edge 2 of which terminates in corners 75 3 cut at an angle to edge 2 and ends 4. It is to be understood that the inner edge 5 will be suitably fastened to an ordinary band 15 (Fig. 17) of a collar in the final step of forming the complete collar.

After the first step of the process has been completed; to wit, the forming of the blank, as shown in Fig. 1, with the outer corners cut at an angle to the ends, then I fold the corners 3 on lines 6, as shown in 85 Fig. 3.

After this first fold 7 has been formed upon the corners of the blank 1, I fold the ends 4 on line 8, Fig. 5, producing the end folds 9, Fig. 6.

After the corner fold 7 and the end folds 9 are produced, I crease, on a creasing machine, the blank on line 10; then the longitudinal edge 2 is folded over to form the longitudinal fold 11, Fig. 9.

The next step in the process involves the folding of the ends of the blank on line 12 and the longitudinal folded edge on line 13, Fig. 10, producing the finished blank or body of the collar, as shown in Fig. 11.

In Fig. 16 I have shown more clearly the result of the creasing action of a creasing machine along the lines 12 and 13, per Fig. 10.

After the plurality of folding actions have been taken, to complete the folding of

the blank at its ends, corners and one of its longitudinal edges, the blank with its folded ends and longitudinal edge is stitched by a double row of stitching 14, Figs. 12 to 5 14.

After the blank or body of the collar (Figs. 11 and 13) has been produced, the same is attached along its inner longitudinal edge 5 to the ordinary band 15 of a collar, resulting in the completion of my improved collar (Fig. 17).

While I have described the preferred embodiment of my invention, and have illustrated the same in the accompanying drawings, certain minor changes or alterations may appear to one skilled in the art to which this invention relates, during the extensive manufacture of the same and I, therefore, reserve the right to make such alterations or changes as shall fairly fall within the scope of the appended claims.

What I claim is:

1. The process of making the body of a collar which comprises cutting the elongated blank strip diagonally at its corners to produce comparatively short corners extending at angles to the ends and longitudinal edges of the blank strip, then folding two of said corners over upon the blank strip, then 20 folding the ends over upon the blank strip, then folding the longitudinal edges contiguous to the folded corners over upon the blank strip, then folding the ends over again upon the blank strip, this last folding of the 30 ends including a folding of one half of each folded corner, then folding the folded longitudinal edge over upon the blank strip, this last folding of the longitudinal edge including the folding of the remaining edges of 40 the folded corners and then permanently uniting the folded portions of the collar.

2. The process of making the body of a collar comprising cutting the elongated blank strip diagonally at its outer corners 45 to produce thereat comparatively short corners extending at oblique angles to the ends and longitudinal edges of the strip, then folding said corners over upon the blank

strip, then folding the ends including the folded corner portions over upon the blank 50 strip, then folding the longitudinal edge contiguous to the folded corners over upon the blank strip, and then folding the ends over again upon the blank strip, and finally folding the folded longitudinal edge over 55 again upon the blank strip, and then permanently uniting the folded portions.

3. A collar, the body portion of which is formed of a blank strip with its outer corners cut diagonally across said body portion, and 60 with a primary fold of the diagonal corners, a secondary fold of the ends including the folded corners, a third fold of the longitudinal edge, a fourth fold of the ends, and a final second fold of the longitudinal edge, 65 with means for uniting the folds.

4. A collar including a body portion formed of a blank cut with short diagonal outer corners, a primary fold of the corners and a series of successive folds of the ends 70 and longitudinal edge, which folds include the second folding of the folded corners, whereby the completed body portion of the collar is given a long pointed construction, 75 all as set forth.

5. The process of making the body of a collar comprising the cutting of an elongated blank strip diagonally at its corners to produce comparatively short corners which extend at oblique angles to the ends and longitudinal edges of the blank strip, then folding two of said corners over upon the blank strip, then folding the ends over upon the blank strip, then folding the longitudinal edge contiguous to the folded corners over 80 upon the blank strip then folding the ends over again upon the blank strip, this last folding of the ends including the folding of one half of each folded corner, then folding the folded longitudinal edge over again upon the blank strip, this last folding of the longitudinal edge including the folding of the remaining halves of the folded corners. 85

In testimony whereof I hereunto affix my signature.

JOHN V. McNAMARA.
